UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

HAULAGE MECHANISM

Application filed February 20, 1928. Serial No. 255,803.

This invention relates to haulage mechanism and more particularly, but not exclusively, to improved clutch means between a pair of relatively rotatable cable winding drums for connecting the drums together for simultaneous rotation.

An object of this invention is to provide an improved haulage mechanism. A further object is to provide improved haulage mechanism including a pair of relatively rotatable haulage or cable winding drums and improved clutch means for connecting said drums together for simultaneous rotation. A still further object is to provide improved clutch means between a pair of coaxially arranged, relatively rotatable, haulage or cable winding drums, one of which is normally power driven, for connecting the free drum to the power driven drum for rotation therewith, the improved clutch means being carried by the drum which is normally freely rotatable. Yet another object is to provide improved friction clutch means between a pair of relatively rotatable haulage or cable winding drums for frictionally connecting the drums together for simultaneous rotation, the clutch means being of improved compact and rugged design especially adapted to the service conditions encountered.

With these and other objects in view the invention consists of certain novel features of construction and the combinations and arrangements of parts as will hereinafter more fully be described, and more particularly pointed out in the appended claims.

In the accompanying drawings there is shown for purposes of illustration one form which the invention may assume in practice.

In these drawings,

Fig. 1 is a central longitudinal vertical sectional view taken through the feeding mechanism of a flexibly fed mining machine with which the improved haulage mechanism is incorporated.

Fig. 2 is a transverse horizontal sectional view partially in elevation, illustrating the improved clutch means and the cable winding drums associated therewith, the view being taken substantially on line 2—2 of Fig. 1.

Figs. 3 and 4 are detail sectional views

taken substantially on lines 3—3 and 4—4 respectively of Fig. 2.

In this illustrative embodiment of the invention the improved haulage means is shown incorporated in the feeding mechanism of a flexibly fed coal mining machine which is herein of the same general type as that described in my copending application Serial No. 179,357, filed March 29, 1927, the clutch means provided herein being an improvement over the clutch means disclosed in the aforesaid application. As shown, a machine frame 1 is provided having a plane bottom surface 2 on which the machine is slidable on the mine floor under the propulsion of the haulage mechanism hereinafter disclosed. Carried by the machine frame 1 is a motor (not shown) which drives through suitable connections the final driving pinion 5 of a plural speed frictionally controlled transmission mechanism, as clearly described in my copending application mentioned above. The pinion 5 meshes with an internal gear 6 herein formed integral with the upper haulage or cable winding drum 7, the hub 8 of which is rotatably mounted on spaced aligned ball bearings 9 supported by a central upstanding sleeve portion 10 herein preferably formed integral with the lower haulage or cable winding drum 11. The haulage drums 7 and 11 are coaxially arranged and are rotatably mounted on a vertical axis as shown in Fig. 1. The hub portion 10 of the lower haulage drum 11 is rotatably mounted on ball bearings 12 suitably carried within the machine frame 1, the lower bearing 12 being carried by a detachable bottom plate 13. The bottom plate 13 is rigidly secured to the machine frame by suitable means including a vertical stud 14, the latter passing coaxially through the hub 10. As illustrated, interposed between the hub 8 of the haulage drum 7 and the hub 10 of the haulage drum 11 is a suitable oil retaining ring 15, while interposed between the lower drum 11 and the bottom plate 13 is a similar oil retaining ring 16, and these rings further prevent access of dirt or other foreign substances to the drum bearings.

In this instance the hub of the haulage

drum 7 has keyed thereto at 17 and arranged coaxially therewith a rotatable clutch drum 18 having a smooth peripheral surface 19, the clutch drum 18 projecting downwardly into a recess within the lower haulage drum 11 and having a depending flange encircling the lower portion of the drum hub 10. Supported on the lower horizontal flange or web portion 20 of the lower haulage drum 11 and disposed within the recess therein are a plurality of clutch shoes or segments 21, herein in four, having riveted thereto on their inner vertical surfaces strips of suitable friction material 22 adapted to frictionally engage the smooth peripheral surface of the clutch drum 18 as will later be described. As clearly shown in Fig. 2, the clutch shoes 21 each have formed thereon an arcuate eccentrically formed or cam surface 23 with which pressure rollers 24 cooperate, the rollers 24 being rotatably mounted on vertical pins 25 carried by a rotatable annular pressure plate or ring 26 arranged coaxially with the drum axes and housed in the recess between the upper and lower drums. The ring 26 has upstanding projections or lugs 27, herein four, having oppositely disposed abutment surfaces 28 and 29. Interposed between and projecting outwardly from the haulage drums 7 and 11 and supported on the annular pressure plate 26 is a control wheel 30 having a plurality of inwardly extending radial projections 31, herein four, having oppositely disposed abutment surfaces alternatively engageable with the abutment surfaces 28, 29 on the projections 27. In accordance with this illustrative embodiment of the invention there are shown upstanding driving blocks 32 fixed to the web 20 of the haulage drum 11 (see Fig. 4) and interposed between the ends of the clutch sleeves 21, and these blocks have inwardly converging surfaces 33 engageable with inclined surfaces 34 formed on each end of the clutch segments 21.

It will be noted that the various elements of the clutch are housed within the recess in the lower haulage drum 11 which is normally disconnected or free from the upper haulage drum 7, the clutch parts rotating with the upper haulage drum 7 only when the clutch is applied. As a result wear is reduced to a minimum and all possibility of the lower haulage drum 11 being accidentally connected to the upper drum due to the automatic application of the clutch which would be possible if the clutch parts rotated with the upper haulage drum is eliminated, it having heretofore been found that such a condition was present when the clutch parts were carried by and rotated with the power driven drum 7.

The operation of the improved haulage mechanism is as follows. Let it be assumed that the pinion 5 is operatively connected to the motor and the upper haulage drum 7 is being rotated by power from the motor, the pinion 5 meshing with the internal gear on the drum 7 driving the latter. When it is desired to effect rotation of the bottom drum 11 with the top drum 7, the operator grasps the control wheel 30 and manually rotates the pressure plate or ring 26 in a counterclockwise direction from the position shown in Fig. 2, thereby causing the pressure rollers 24 to move along the eccentric or cam surfaces 23 on the clutch shoes, forcing the latter inwardly into engagement with the peripheral surface of the clutch drum 18 and as a result the lower haulage drum 11 is frictionally connected to the upper haulage drum 7 for rotation therewith. At this time the haulage drum 11 is driven from the upper haulage drum 7 through the upper drum hub 8, clutch drum 18, clutch shoes 21 and driving blocks 32 fixed to the lower haulage drum 11. When the haulage drum 11 is driven by the drum 7 and is under load, the inwardly converging surfaces on the driving blocks 32 act against the correspondingly inclined surfaces on the clutch shoes thereby forcing the latter inwardly to apply the clutch and thereby supplementing the action of the pressure rollers 24. It will also be obvious that upon suitable release of the control wheel 30 the lower haulage drum 11 may be disconnected from the upper haulage drum 7, that is, when the control wheel is moved in a clockwise direction from the position shown in Fig. 2 wherein the projections 31 engage the surfaces 28 to a position wherein the projections 31 engage the surfaces 29, rotation of the pressure plate 26 in a clockwise direction to the position shown in Fig. 2 releasing the pressure of the rollers 24 from the cam surfaces 23 and thereby releasing the clutch.

As a result of this invention it will be noted that an improved haulage mechanism is provided comprising coaxially arranged, relatively rotatable haulage or cable winding drums and having improved friction clutch means between the drums for frictionally connecting the drums together for simultaneous rotation, the clutch means being of an improved rugged and compact design especially adapted to the service conditions encountered. It will further be noted that the improved clutch means is so constructed that the elements thereof normally remain stationary with the lower free drum and rotate only upon the application of the clutch and when the lower drum is driven by the upper power driven drum. It will still further be noted that by arranging the clutch parts within the normally free lower haulage drum the wear of the clutch parts is reduced to a minimum and furthermore the possibility of automatic and unintentional application of clutch which was present when the clutch parts rotated with the upper power driven drum is eliminated. These and other uses

and advantages of this invention will be clearly apparent to those skilled in this art.

While in this application one form which the invention may assume in practice has been specifically described, it will be understood that this form of the same is shown for purposes of illustration and that the same may be modified and embodied in various other forms without departing from its spirit or the scope of the appended claims.

What I claim as new and desire to secure by Letters Patent is:

1. In a haulage mechanism, relatively rotatable haulage drums of the same size one of which is power driven while the other is freely rotatable, and clutch means carried by said freely rotatable drum for connecting the latter to said power driven drum for rotation in the same direction therewith, said clutch means including clutch elements movable relative to said freely rotatable drum to effect connection between said drums and normally stationary with said freely rotatable drum when in their released position.

2. In a haulage mechanism, relatively rotatable coaxially arranged haulage drums of the same size one of which is power driven while the other is freely rotatable, and clutch means carried by said freely rotatable drum for connecting the latter to said power driven drum for rotation therewith, said clutch means including clutch elements movable relative to said freely rotatable drum to effect connection between said drums and normally stationary with said freely rotatable drum when in their released position.

3. In a haulage mechanism, relatively rotatable coaxially arranged haulage drums arranged in substantially end abutting relation and rotatable about a vertical axis, one of which is power driven while the other is freely rotatable, and clutch means housed within said drums and carried by said freely rotatable drum for connecting the latter to said power driven drum for rotation therewith.

4. In a haulage mechanism, relatively rotatable coaxially arranged haulage drums of the same diameter, power operated driving connections for one of said drums, and clutch means carried by said other drum for connecting said latter drum to said first mentioned drum for rotation therewith, said clutch means including clutch elements movable relative to said drums by which they are carried to effect connection between said drums and normally stationary with said latter drum when in their released position.

5. In a haulage mechanism, relatively rotatable coaxially arranged haulage drums of the same diameter, power operated driving connections for one of said drums, and clutch means carried by said other drum for connecting said latter drum to said first mentioned drum for rotation therewith, said clutch means including clutch elements mov-

able relative to said drum by which they are carried to effect connection between said drums and normally stationary with said latter drum when in their released position and controlling means for said clutch means including a controlling element interposed between and projecting outwardly from said drums.

6. In a haulage mechanism, relatively rotatable coaxially arranged haulage drums, power operated driving connections for one of said drums, clutch means carried by said other drum for connecting said latter drum to said first mentioned drum for rotation therewith, and controlling means for said clutch means including a control wheel arranged coaxially with and interposed between said drums.

7. In a haulage mechanism, a pair of relatively rotatable coaxially arranged haulage drums, one of said drums having a hub portion on which said other drum is journaled, power operated driving connections for one of said drums, and clutch means controllable to effect clutching or release and carried by said other drum for connecting said drums together for simultaneous rotation.

8. In a haulage mechanism, a pair of relatively rotatable coaxial haulage drums arranged in substantially end abutting relation and disposed on a vertical axis, power operated driving connections for the upper drum, and clutch means controllable to effect clutching or release and housed within said drums and carried by the lower drum for connecting said drums together for simultaneous rotation.

9. In a haulage mechanism, a pair of relatively rotatable coaxial haulage drums arranged in close adjacency and disposed on a vertical axis, power operated driving connections for the upper drum, and clutch means controllable to effect clutching or release and carried by and housed within the lower drum for connecting said drums together for simultaneous rotation, said upper drum forming a closure for housing said clutch means within the lower drum.

10. In a haulage mechanism, a pair of relatively rotatable coaxial haulage drums arranged in close adjacency and disposed on a vertical axis, power operated driving connections for the upper drum, and clutch means carried by and housed within the lower drum for connecting said drums together for simultaneous rotation and controlling means for said clutch including a control element interposed between and projecting outwardly through the relatively narrow space between the flanges of said drums, said clutch means including clutch elements movable relative to the lower drum to effect connection between said drums and normally stationary with the lower drum when in their released position.

11. In a haulage mechanism, a pair of rela-

tively rotatable coaxial haulage drums disposed on a vertical axis, power operated driving connections for the upper drum, and clutch means controllable to effect clutching or release and carried by and housed within the lower drum for connecting said drums together for simultaneous rotation and controlling means for said clutch including a control wheel arranged coaxially with and interposed between said drums.

12. In a haulage mechanism, coaxially arranged upper and lower haulage drums, the upper drum being journaled on and supported by the lower drum, and means for connecting said drums together for simultaneous rotation including clutch means controllable to effect clutching or release and housed within and rotatable with said lower drum for clutching the latter to said upper drum.

13. In a haulage mechanism, a pair of relatively rotatable haulage drums, and friction clutch means for connecting said drums together for simultaneous rotation including a clutch drum rotatable with one haulage drum and projecting into the other and friction means carried by the other haulage drum and engageable with said clutch drum for connecting said drums together.

14. In a haulage mechanism, a pair of relatively rotatable haulage drums, and friction clutch means for connecting said drums together for simultaneous rotation including a clutch drum rotatable with one haulage drum and projecting into the other, clutch shoes carried by said other haulage drum, and means carried by said latter haulage drum for forcing said clutch shoes into frictional engagement with said clutch drum.

15. In a haulage mechanism, a pair of relatively rotatable haulage drums and friction clutch means for connecting said drums together for simultaneous rotation including a clutch drum rotatable with one haulage drum, clutch shoes carried by said other haulage drum, means carried by said latter haulage drum for forcing said clutch shoes into frictional engagement with the external periphery of said clutch drum, and cam operating means including cam surfaces on said clutch shoes for applying said clutch.

16. In a haulage mechanism, a pair of relatively rotatable haulage drums and friction clutch means for connecting said drums together for simultaneous rotation including a clutch drum rotatable with one haulage drum and projecting into the other, clutch shoes carried by said other haulage drum, means carried by said latter haulage drum for forcing said clutch shoes into frictional engagement with said clutch drum, and cam operating means including cam surfaces on said clutch shoes and cooperating pressure rollers for engaging said cam surfaces for applying said clutch.

17. In a haulage mechanism, a pair of rela-

tively rotatable haulage drums, and friction clutch means for connecting said drums together for simultaneous rotation including a clutch drum rotatable with one haulage drum, frictional means carried by said other haulage drum and engageable upon movement towards the axis of said clutch drum with said clutch drum and cam operating means for applying said clutch including pressure rollers and rotatable control means for actuating said rollers for applying said clutch.

18. In a haulage mechanism, a pair of relatively rotatable coaxial haulage drums disposed on a vertical axis, clutch means controllable to effect clutching or release and carried by the bottom drum and rotatable therewith for connecting said drums together, and rotatable cam operating means including a rotatable control element coaxial with said drums for applying said clutch.

19. In a haulage mechanism, a pair of relatively rotatable upper and lower haulage drums of the same size, and clutch means carried by and rotatable with the lower drum for connecting said drums together for simultaneous rotation, said clutch means including clutch elements movable relative to the lower drum to effect connection between said drums and normally stationary with the lower drum when in their released position.

20. In a haulage mechanism, relatively rotatable cable winding drums of the same size and capacity, one of which is power driven while the other is freely rotatable, and clutch means carried by said freely rotatable drum and including a clutch element movable relative to the latter for connecting said freely rotatable drum to said power driven drum for rotation in the same direction therewith, said clutch means including clutch elements movable relative to said freely rotatable drum to effect connection between said drums and normally stationary with said freely rotatable drum when in their released position.

21. In a haulage mechanism, a pair of relatively rotatable upper and lower cable winding drums arranged in superimposed relation in close adjacency with one another, and clutch means carried by and rotatable with the lower drum and including a clutch element movable relative to the latter for connecting said drums together for simultaneous rotation, said upper drum forming a closure for housing said clutch means with in the lower drum.

In testimony whereof I affix my signature.
MORRIS P. HOLMES.
